GROUTING MACHINE

Harold F. Zagray, Canton, and Floyd W. Wack, Louisville, Ohio, assignors to Precision Building System, Inc., Canton, Ohio, a corporation of Ohio

Application December 1, 1954, Serial No. 472,408

13 Claims. (Cl. 259—152)

The invention relates to grouting machines and more particularly to certain improvements upon the type of grouting machine shown in the prior Patent No. 2,633,340, dated March 31, 1953, issued upon application of Harold F. Zagray and Floyd W. Wack.

Such grouting machines are especially adapted for use in erecting masonry walls of building blocks or bricks of the general type disclosed in Stewart Patent No. 2,558,630, dated June 26, 1951 and in prior patents to Harold F. Zagray No. 2,634,602, dated April 14, 1953 and No. 2,655,032, dated October 13, 1953.

Building blocks or bricks of this general type have vertical openings therethrough and communicating horizontal and vertical grooves in the top, bottom and end walls thereof, forming mortar passages located entirely within the outlines of the block or brick.

Such building blocks or bricks are laid up dry, in a wall of considerable height, after which grout is poured into the openings in the uppermost course of blocks, filling all of the communicating openings and grooves of the blocks with grout, which, upon hardening, forms a continuous network of mortar entirely within the outline of the blocks.

Grouting machines of the character to which the invention pertains, are used for pouring or forcing grout into this network of communicating passages, and include a pump, and a hose line by means of which the grout may be carried to a considerable height and poured or pumped into the openings in the uppermost course of the wall.

Prior to my invention, grouting machines of this general type were provided with a single mixing tank or reservoir, from which the grout was withdrawn to a pump from which it was discharged through a hose line.

Such machines do not satisfactorily mix and blend the ingredients of the grout, and do not have satisfactory facilities for thoroughly cleaning the grout therefrom, after a grouting operation is completed. Furthermore, they do not have means for operating either the pump or the mixing tank independently of the other.

It is therefore an object of the present invention to provide a grouting machine which overcomes the above-named disadvantages and difficulties, and which embodies certain improvements upon grouting machines of this general type.

Another object is to provide a grouting machine having a first or initial and a second or final mixing tank, the grout being initially mixed in the first mixing tank and then discharged into the second mixing tank, which also functions as a reservoir from which the grout is withdrawn to the pump.

A further object is to provide means for operating either of the mixing tanks or the pump, independently of the others.

A still further object is to provide such a grouting machine, in which the first or initial mixing tank is mounted for tilting in opposite directions, whereby the contents thereof, when properly mixed, may be dis-

2

charged into the reservoir, or final mixing tank, or may be discharged, through a grating or chute, onto the ground when it is desired to clean the machine after a grouting operation is completed.

5 Another object of the invention is to provide a grouting machine of the character referred to, in which the discharge outlet of the first or initial mixing tank is covered with a screen, and agitating paddles in said mixing chamber wipe the grout through said screen.

10 A further object is to provide a grouting machine of this type in which the wiping paddles in the initial mixing tank are formed of rubber or similar flexible material.

15 A still further object is to provide such a machine with convenient and readily operable facilities for cleaning out and flushing the mixing tanks, pump and hose line after use of the machine.

Another object of the invention is to provide means for continuously recirculating grout from the pump to 20 the final mixing tank, during short periods when the machine is not in use, in order to prevent clogging of the hose line.

25 A further object is to provide a water line in the machine, with hose connections for furnishing water to the initial mixing tank and to the pump.

30 A still further object is to provide such a grouting machine, permanently mounted upon a truck, whereby the machine is easily transported and may be readily moved from one location to another, as may be required, during the building of a masonry wall.

The above and other objects, apparent from the drawings and following description, may be attained, the above described difficulties overcome and the advantages and results obtained, by the apparatus, construction, arrangements and combinations, subcombinations and parts which comprise the present invention, a preferred embodiment of which, illustrative of the best mode in which applicant has contemplated applying the principle, being set forth in detail in the following description and illustrated in the accompanying drawings forming a part hereof.

35 The invention may be described in general terms, as comprising a portable grouting machine, permanently mounted upon a specially constructed truck bed, for ease in transportation and in moving the machine to different positions adjacent to a masonry wall under construction. An initial mixing tank is pivotally mounted upon the truck bed for tilting in one direction to pour mixed grout into a second or final mixing tank, mounted at a lower position upon the truck bed, or in the opposite direction for pouring any remaining grout through an opening or grating in the truck bed, in order to clean said initial mixing tank after a grouting operation has been completed.

40 45 50 55 The discharge outlet of the initial mixing tank is covered with a wire mesh screen, and a rotatable agitator is located within said initial mixing tank and provided with paddles of rubber or the like contacting said screen for wiping the grout therethrough.

An inlet opening is formed in the initial mixing tank adjacent to the discharge outlet, a grating being located over said inlet opening and a serrated blade is located transversely across the center of the inlet opening for cutting or breaking open bags of cement and the like to permit the contents thereof to be poured into the initial mixing tank.

60 65 70 75 Grout is withdrawn from the second or final mixing tank by a pump which discharges the grout through a hose line provided with a nozzle and shut-off valve. Means is provided for driving the agitators in the mixing tanks, and the pump, from the conventional power take-off of the truck, with separate clutches for independently

connecting either mixing tank or the pump to the power means.

A water line is provided with hose connections for attaching a hose to furnish water to the initial mixing tank, and for connecting a hose to the pump for flushing and cleaning the same after use, and a hose connection is provided on the second or final mixing tank for connecting the return hose line thereto, or, in the event a single hose line is used, for connecting the end thereof to the final mixing tank, so as to continually recirculate grout from the pump to said mixing tank during periods when the machine is being moved from one position to another.

A preferred embodiment of the invention thus set forth in general terms, is illustrated in the accompanying drawings, in which:

Fig. 1 is a rear elevation of a grouting machine embodying the invention, showing the pump which forces the grout through the flexible hose, viewed as on the line 1—1, Fig. 2, showing the parts in the normal position;

Fig. 2 is a top plan view of the improved grouting machine, showing the parts in the same positions as in Fig. 1;

Fig. 3 is a section taken as on the line 3—3, Fig. 2, showing the front side of the grouting machine in elevation;

Fig. 4 is a transverse sectional view, taken as on the line 4—4, Fig. 2, showing one end of the grouting machine in elevation, and illustrating the sprocket chain drive;

Fig. 5 is a section taken as on the line 5—5, Fig. 1, showing the opposite end of the grouting machine in elevation;

Fig. 6 is a transverse sectional view on the line 6—6, Figs. 1 and 2, showing the initial mixing tank in full lines tilted to position to pour grout into the final mixing tank, and in broken lines tilted to position to empty grout through the grating in the floor of the truck; and

Fig. 7 is a detached perspective view of the rotary agitator shaft and paddles in the initial mixing tank.

Reference is now made to the detail construction and operation of the embodiment of the invention illustrated in the drawings, in which similar numerals refer to similar parts throughout.

The grouting machine to which the invention pertains is preferably permanently mounted upon a motor truck, a portion of the floor of which is indicated at 10. A fixed, final mixing tank 11, of generally cylindrical shape, and an oscillatory, initial mixing tank 12, also of generally cylindrical form, comprise important parts of the grouting machine.

The final mixing tank 11 is mounted partially below the level of the floor 10 of the truck, the lower portion of said tank being located through an opening 13 in the floor, as best shown in Fig. 6.

A drain 14 is located in the bottom of the final mixing tank, below the truck floor 10, and is normally closed as by the screw plug 15, whereby any grout remaining in the final mixing tank may be drained onto the ground, and the tank may be flushed and cleaned so that it is in proper condition for use again.

For the purpose of keeping the grout in the final mixing tank in proper condition for use, a continuously rotating agitator is provided therein. This agitator comprises the shaft 16, concentrically journaled longitudinally through the tank 11, and having a plurality of groups of paddles or blades thereon.

Each group of paddles or blades comprises a radially disposed arm 17, fixed upon the shaft 16, and having a plurality of spaced, angularly disposed paddles 18 fixed thereon, throughout its length, and a wiper blade 19 at its outer end, having an arcuate outer edge portion 20 for wiping contact with the inner walls of the cylindrical tank 11.

Preferably, there are four groups of these paddles and

blades, two groups being connected to the middle portion of the shaft 16, diametrically opposite to each other, as indicated at a—a, the other two groups being located one near each end of the shaft, as indicated at b—b, each of the latter groups having a radially disposed blade 21 for wiping the adjacent end wall of the tank.

For the purpose of admitting grout to the final mixing tank, from the initial mixing tank 12, an inlet opening 22 is provided in the upper portion of the final mixing tank, and preferably extends from the top of the tank, as indicated at 23, to a point on the side toward the initial mixing tank, as indicated at 24.

The initial mixing tank 12 is rotatably mounted upon bearings 25, mounted upon the upper ends of uprights 26, which are supported upon the floor 10. Journals 27 are attached to opposite ends of the tank 12, and journaled in the bearings 25, whereby the initial mixing tank may be oscillated from the normal position shown in Figs. 1 to 5, to the positions shown in Fig. 6.

An inlet opening 28 is provided in the initial mixing tank 12, and preferably provided with a series of spaced longitudinally disposed rods or bars forming a grating 29 thereon, with a central, transversely disposed, serrated blade 30 for cutting or tearing open paper sacks of cement or a mixture of cement and aggregate suitable for making grout. The grating 29 is hinged at one side of the opening 28, as shown at 29a.

An agitator, similar to that in the final mixing tank, is located in the initial mixing tank, the shaft 16a thereof having the journal portions 31 at its ends, journaled within the hollow trunnions 27 of the initial tank 12, whereby the agitator may rotate relative to the tank 12.

A plurality of groups of paddles or blades are carried by the shaft 16a, each group comprising a radially disposed arm 17a, fixed upon the shaft 16a, and having a plurality of spaced, angularly disposed paddles 18a fixed thereon, throughout its length, and a wiper blade 19a at its outer end, having an arcuate edge portion 20a, preferably formed of rubber or the like, for wiping contact with the inner walls of the initial mixing tank 12.

There are preferably four groups of these paddles and blades, two groups being connected to the middle portion of the shaft 16a, diametrically opposite to each other, as indicated at a'—a', the other two groups being located one near each end of the shaft, as indicated at b'—b', each of the latter groups having a radially disposed blade 21a for wiping the adjacent end wall of the initial mixing tank 12.

At a point adjacent to the inlet or charging opening 28, the initial mixing tank is provided with an outlet or discharge opening 32, provided with a wire mesh or screen 33, through which the mixed grout may be poured into the final mixing tank 11, when the initial mixing tank is rotated to the position shown in Fig. 6.

An opening 34 is formed in the truck floor 10, at the opposite side of the initial mixing tank from the final mixing tank 11, and is covered with a grating or grill 35, so that any grout remaining in the initial mixing tank may be poured therethrough, onto the ground, at the end of the day's work, by rotating the initial mixing tank to the broken line position shown in Fig. 6.

Referring now more particularly to Figs. 2 and 3, the conventional power take-off shaft of the truck is indicated at 36, and for the purpose of providing means for operating the grouting machine, a universal joint 37 connects this power take-off shaft to the main drive shaft 38 of the grouting machine.

This latter shaft is journaled in suitable bearings 39, mounted upon the angle members 40, supported upon the lower flanges of the channel bars 41, which are suspended from the I-beams 42 of the truck body.

A sprocket wheel 43 is fixed upon the drive shaft 38, and operatively connected, as by the sprocket chain 44, to the relatively large sprocket wheel 45, fixed upon the counter shaft 46. The sprocket wheel 47 is fixed upon

the counter shaft 46, and is connected, as by the sprocket chain 48, to the relatively large sprocket wheel 49, upon the adjacent hollow trunnion 27 of the initial mixing tank.

The shaft 16 of the agitator in the final mixing tank 11 is provided with trunnions 50 at its ends, journaled in bearings 51 at opposite ends of the tank. A relatively large sprocket wheel 52 is fixed upon one of the trunnions 50 and is connected, as by the sprocket chain 53, with a relatively small sprocket wheel 54, upon the shaft 46, whereby the agitator in the final mixing tank may be driven from the main drive shaft 38.

A clutch is provided upon the shaft 50 for operatively connecting the loose sprocket wheel 52 to the shaft 50. This clutch comprises the clutch member 55, fixed to the sprocket wheel 52, and the slideable, keyed clutch member 56 for engagement therewith.

A clutch lever 57 is fulcrumed as at 58 upon a bracket 59, and operatively connected to the sliding clutch 56 in conventional manner, as by the studs 60 upon the clutch member located through slots 61 in the operating lever 57.

In the same manner, a clutch is provided for controlling the agitator in the initial mixing tank; this clutch comprising the clutch member 62 fixed to the loose sprocket 49, on the trunnion 31 of the agitator shaft 16a, and the sliding, keyed clutch member 63 adapted to be operated by the lever 64 fulcrumed as at 65 upon the bracket 66 and connected to the clutch member 63, as by the studs 67 on the clutch member and the slots 68 in the lever.

A pump, indicated generally at 69, of the same general type as the pump disclosed in my prior Patent No. 2,663,340, is provided for pumping grout from the final mixing chamber 11 through a flexible hose to the masonry wall under construction.

This pump comprises a housing 70, having an inlet 71 communicating with the bottom of the final mixing tank 11, and an outlet 72, provided with a hose coupling 73, to which a flexible hose 74 is connected. A helical or screw rotor (not shown) similar to that disclosed in my prior patent above referred to, is located within the housing 70, and the shaft 75 of said rotor is extended through the opposite end of the housing, from the outlet 72.

Brackets 76 and 77, depending from the final mixing tank 11 and the truck body respectively, support the pump housing 70 parallel to the mixing tanks at one side of the truck body.

A clutch member 78 is rotatably mounted upon the pump shaft 75, and has a sprocket wheel 79 fixed thereto, and connected, by the chain 80, with the sprocket wheel 81 upon the main drive shaft 38. The clutch member 82 is slidably keyed upon the pump shaft 75, and adapted to be moved into engagement with the rotating clutch member 78 by the lever 83, fulcrumed at 83' upon the truck frame and extending to the opposite side of the machine.

The lever 83 has a yoke 84 thereon, having slots 85 therein which receive the studs 86 on the sliding clutch member 82, and an operating handle 87 is fixed to the lever 83 and extends outwardly on the pump side of the machine, then the pump may be started or stopped, either by an operator standing on the truck adjacent to the initial mixing tank, or by another operator standing on the ground at the pump side of the truck.

The flexible hose 74 may be of any desired length required for the height to which the grout must be pumped, and is provided at its outer end with a nozzle 88, having a cut-off valve 89 thereon, whereby the discharge of grouting material therefrom may be manually controlled.

For the purpose of preventing the grouting material from hardening in the hose 74, when the valve 89 is closed, a return hose line 90 communicates with the hose 74 adjacent to the nozzle 88, and is connected at its other end to the hose coupling 91 which communicates with the upper portion of the final mixing tank 11.

A T-connection 92 is interposed in the hose line 74,

between the nozzle 88 and the return hose 90, and is provided with a valve 93, of any suitable type. This valve 93 may be closed during normal operation, when the shut-off valve 89 is open, but, if the shut-off valve 89 is closed for any considerable length of time, the valve 93 is open so that grouting material may be continuously pumped from the final mixing tank 11, through the hose 74 and back through the return hose 90 to the tank 11, whereby the grouting material will remain at proper consistency and the machine is at all times ready for operation by merely closing the valve 92 and opening the shut-off valve 89.

For the purpose of furnishing water to the machine, a pipe line 94 is located transversely of the truck and provided, at the pump side of the machine, with a threaded nipple 95 to which a hose may be connected, for attachment to a faucet or the like.

At the other side of the machine, the pipe line 94 is disposed vertically, as shown at 96, and terminates in a downwardly directed spout 97, for discharging water into the initial mixing tank 12, as through the screened opening 32 thereof. A valve 98 is provided for controlling the discharge of water through the spout 97.

A T-connection 99 is provided in the upright pipe 96, 25 and a short length of pipe 100 is attached thereto, the outer end thereof being threaded, as shown at 101, for attaching a hose for flushing and cleaning the final mixing tank, after a day's work.

In order to flush out and clean the pump, after use, 30 a pipe 102 connects the water supply pipe 94 into the interior of the pump housing 70, and is provided with a normally closed valve 103, which may be opened where it is desired to flush the pump.

It should be understood that, if desired, the return hose 35 90 may be dispensed with. In this case, whenever the nozzle 88 is not in use for a short period of time, it may be detached from the hose 74, and the end of the hose may be attached to the coupling 91 upon the final mixing tank, so that grout will be pumped continuously through 40 said hose and returned to the final mixing tank.

In the operation of the machine, the desired amounts of cement, aggregate and water are charged into the initial mixing tank, and are thoroughly mixed to the proper consistency therein by the rotating agitator blades. The initial mixing tank is held in the position shown in Fig. 5, by the operating rod 104, located through the eye 105 on the side of the tank 12, the inner end of the rod 104 contacting the stop 106, pivoted as at 107 upon the bracket 108.

50 After the grout is mixed to proper consistency in the initial mixing tank 12, the operator grasps the rod 104 and oscillates the tank 12 to the position shown in Fig. 6, discharging the grout from the initial mixing tank 12, through the screen 33, into the final mixing tank.

55 The rubber tipped blades 20a, of the agitator in the initial mixing tank, wipe the grout through the screen 33, so that the grout is smooth and free from any hard lumps or oversize particles of aggregate.

The grouting material is continually agitated after it is charged into the final mixing tank, and is withdrawn therefrom by the pump, and pumped through the hose line 94 to the desired location and height, where it is discharged from the nozzle 88 into the mortar spaces of the masonry wall under construction.

60 It will be seen that the agitators in each of the mixing tanks, as well as the pump, may be operated independently, by manual operation of the respective clutch levers, and that the pump clutch may be manually operated from either side of the machine.

65 After the day's work is completed, any grout still remaining in the initial mixing tank may be discharged therefrom, through the grating 35 in the truck floor, by tilting said tank to the broken line position shown in Fig. 6.

70 For this purpose, the rod 104 is removed from the eye

105 on the end of the initial mixing tank 12, and inserted into the eye 110, and the pivoted stop 106 is thrown up, out of the path of said rod.

The final mixing tank 11 may be drained of any remaining grout, by removing the clean-out plug 15, and both tanks may be thoroughly flushed and washed by a hose attached to the coupling 101 of the water supply pipe, the valve 111 being of course opened for this purpose.

By opening the valve 103, in the pipe 102, the pump and hose line 74 may be thoroughly flushed and washed, so that all grout is entirely removed from the machine, and it is ready for use whenever desired.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful construction, and reasonable mechanical equivalents thereof obvious to those skilled in the art, are set forth in the appended claims.

We claim:

1. A grouting machine comprising a final mixing tank, agitating means therein, an initial mixing tank, agitating means in the initial mixing tank, means pivotally mounting the initial mixing tank above the final mixing tank, there being a discharge outlet in the upper portion of the initial mixing tank, means for tilting the initial mixing tank to discharge the contents thereof through said outlet into the final mixing tank, means for tilting the initial mixing tank away from the final mixing tank to discharge the contents thereof, a pump having an inlet and an outlet, means connecting the final mixing tank to the pump inlet, a flexible hose connected to the pump outlet, a prime mover and means for independently operatively connecting the prime mover to the pump and to each of said agitating means.

2. A grouting machine comprising a final mixing tank, agitating means therein, a hose connection on the final mixing tank, an initial mixing tank, agitating means in the initial mixing tank above the final mixing tank, there being a discharge outlet in the upper portion of the initial mixing tank, means for tilting the initial mixing tank to discharge the contents thereof through said outlet into the final mixing tank, means for tilting the initial mixing tank away from the final mixing tank to discharge the contents thereof, a pump having an inlet and an outlet, means connecting the final mixing tank to the pump inlet, a flexible hose connected to the pump outlet, means for connecting the end of said flexible hose to said hose connection for recirculating grout from the pump to said final mixing tank, a prime mover and means for independently operatively connecting the prime mover to the pump and to each of said agitating means.

3. A grouting machine comprising a final mixing tank, agitating means therein, an initial mixing tank, agitating means in the initial mixing tank, means pivotally mounting the initial mixing tank above the final mixing tank, there being a discharge outlet in the upper portion of the initial mixing tank, means for tilting the initial mixing tank to discharge the contents thereof through said outlet into the final mixing tank, means for tilting the initial mixing tank away from the final mixing tank to discharge the contents thereof, a pump having an inlet and an outlet, means connecting the final mixing tank to the pump inlet, a flexible hose connected to the pump outlet, a prime mover, and means for independently operatively

connecting each of said agitating means and said pump to said prime mover.

4. A grouting machine comprising a final mixing tank, agitating means therein, an initial mixing tank, rotatable agitating means in the initial mixing tank, means pivotally mounting the initial mixing tank above the final mixing tank, there being a discharge outlet in the upper portion of the initial mixing tank, a relatively fine mesh screen covering said discharge outlet, said rotatable agitating means including paddles for wiping contact with said screen, means for tilting the initial mixing tank to discharge the contents thereof through said outlet into the final mixing tank, said paddles wiping grout through said screen when the initial mixing tank is tilted to discharge position, a pump having an inlet and an outlet, means connecting the final mixing tank to the pump inlet, a flexible hose connected to the pump outlet, and a prime mover operatively connected to the pump and to said agitating means.

5. A grouting machine comprising a final mixing tank, agitating means therein, an initial mixing tank, rotatable agitating means in the initial mixing tank, means pivotally mounting the initial mixing tank above the final mixing tank, there being a discharge outlet in the upper portion of the initial mixing tank, a relatively fine mesh screen covering said discharge outlet, said rotatable agitating means including flexible paddles for wiping contact with said screen, means for tilting the initial mixing tank to discharge the contents thereof through said outlet into the final mixing tank, flexible paddles wiping grout through said screen when the initial mixing tank is tilted to discharge position, a pump having an inlet and an outlet, means connecting the final mixing tank to the pump inlet, a flexible hose connected to the pump outlet, and a prime mover operatively connected to the pump and to said agitating means.

6. A grouting machine comprising a final mixing tank, agitating means therein, an initial mixing tank, agitating means in the initial mixing tank, means pivotally mounting the initial mixing tank above the final mixing tank, there being a discharge outlet in the upper portion of the initial mixing tank and an inlet opening adjacent to the discharge opening, means for tilting the initial mixing tank in one direction to discharge the contents thereof through said discharge outlet into the final mixing tank, means for tilting the initial mixing tank in the opposite direction for emptying the contents thereof through said inlet opening, a pump having an inlet and an outlet, means connecting the final mixing tank to the pump inlet, a flexible hose connected to the pump outlet, a prime mover and means for independently operatively connecting the prime mover to the pump and to each of said agitating means.

7. In combination with a self-propelled truck having a bed and a power take-off, a grouting machine comprising a final mixing tank mounted upon the truck bed, agitating means therein, an initial mixing tank pivotally mounted upon the truck bed above and at one side of the final mixing tank, agitating means in the initial mixing tank, there being a discharge opening in the truck bed at the opposite side of the initial mixing tank from the final mixing tank, the initial mixing tank having a discharge outlet in its upper portion and an inlet opening adjacent to the discharge outlet, means for tilting the initial mixing tank in one direction to discharge the contents thereof through said discharge outlet into the final mixing tank, means for tilting the initial mixing tank in the opposite direction for emptying the contents thereof through the inlet opening in said initial mixing tank and through said discharge opening in the truck bed, a pump having an inlet and an outlet, means connecting the final mixing tank to the pump inlet, a flexible hose connected to the pump outlet, and means for operatively connecting said agitating means and said pump to said power take-off.

8. In combination with a self-propelled truck having a bed and a power take-off, a grouting machine comprising a final mixing tank mounted upon the truck bed, agitating means therein, an initial mixing tank pivotally mounted upon the truck bed above and at one side of the final mixing tank, agitating means in the initial mixing tank, there being a discharge opening in the truck bed at the opposite side of the initial mixing tank from the final mixing tank, the initial mixing tank having a discharge outlet in its upper portion and an inlet opening adjacent to said discharge outlet, a grating hingedly mounted over said inlet opening, a transversely disposed serrated blade across the center of the inlet opening, means for tilting the initial mixing tank in one direction to discharge the contents thereof through said discharge outlet into the final mixing tank, means for tilting the initial mixing tank in the opposite direction for emptying the contents thereof through the inlet opening in said initial mixing tank and through said discharge opening in the truck bed, a pump having an inlet and an outlet, means connecting the final mixing tank to the pump inlet, a flexible hose connected to the pump outlet, and separate means for independently operatively connecting each of said agitating means and said pump to said power take-off.

9. A grouting machine comprising a final mixing tank, agitating means therein, an initial mixing tank, agitating means in the initial mixing tank, means pivotally mounting the initial mixing tank above the final mixing tank, there being a discharge outlet in the upper portion of the initial mixing tank, stop means upon the initial mixing tank, a pivoted lug upon the machine for contact with said stop means to prevent tilting movement of said initial mixing tank away from the final tank, means for tilting the initial mixing tank to discharge the contents thereof through said outlet into the final mixing tank, means for tilting the initial mixing tank in the opposite direction for emptying the contents thereof through said discharge outlet when said pivoted lug is moved out of the path of said stop means, a pump having an inlet and an outlet, means connecting the final mixing tank to the pump inlet, a flexible hose connected to the pump outlet, a prime mover and means for independently operatively connecting said prime mover to the pump and to each of said agitating means.

10. A grouting machine comprising a final mixing tank, agitating means therein, an initial mixing tank, agitating means in the initial mixing tank, means pivotally mounting the initial mixing tank above the final mixing tank, there being a discharge outlet in the upper portion of the initial mixing tank, means for tilting the initial mixing tank to discharge the contents thereof through said outlet into the final mixing tank, a pump having an inlet and an outlet, means connecting the final mixing tank to the pump inlet, a valve in the pump inlet, means for operating said valve from a point adjacent the initial mixing tank and means for operating said valve from a point adjacent the pump, a flexible hose connected to the pump outlet, a prime mover and means for independ-

60

ently operatively connecting said prime mover to the pump and to each of said agitating means.

11. A grouting machine comprising a final mixing tank, agitating means therein, an initial mixing tank, agitating means in the initial mixing tank, means pivotally mounting the initial mixing tank above the final mixing tank, there being a discharge outlet in the upper portion of the initial mixing tank, a relatively fine mesh screen covering said discharge outlet, there being an inlet opening in the initial mixing tank adjacent to the discharge outlet therein, a grating over said inlet opening, a transversely disposed serrated blade centrally located across said inlet opening, means for tilting the initial mixing tank to discharge the contents thereof through said outlet into the final mixing tank, a pump having an inlet and an outlet, means connecting the final mixing tank to the pump inlet, a flexible hose connected to the pump outlet, a prime mover and means operatively connecting the prime mover to the pump and to said agitating means.

12. A mixing tank for mixing grout and the like, means pivotally mounting said tank, there being a discharge outlet in the upper portion of the tank, a relatively fine mesh screen covering said discharge outlet, there being a filling opening in said tank adjacent to the discharge outlet, a grating over said filling opening, a transversely disposed serrated blade centrally located upon said grating, a rotary agitating means within the tank, flexible paddles upon said agitating means for wiping contact with said screen, and means for tilting the tank upon its pivot to discharge the contents thereof through said screen, said flexible paddles wiping grout through said screen when the tank is tilted to discharge position.

13. A grouting machine comprising a final mixing tank, agitating means therein, an initial mixing tank, rotatable agitating means in the initial mixing tank, means pivotally mounting the initial mixing tank above the final mixing tank, there being a discharge outlet in the upper portion of the initial mixing tank, a relatively fine mesh screen covering said discharge outlet, said rotatable agitating means including rubber paddles for wiping contact with said screen, means for tilting the initial mixing tank to discharge the contents thereof through said outlet into the final mixing tank, said paddles wiping grout through said screen when the initial mixing tank is tilted to discharge position, a pump having an inlet and an outlet, means connecting the final mixing tank to the pump inlet, a flexible hose connected to the pump outlet, and a prime mover operatively connected to the pump and to said agitating means.
